ELECTRICAL CONNECTOR

Einar R. Olson, Richmond, Ind., assignor to
 Belden Manufacturing Company, Chicago, Ill.,
 a corporation of Illinois

Application January 12, 1946, Serial No. 640,825

3 Claims. (Cl. 173—322)

1

The present invention relates to electrical connectors, and particularly to detachable plug connectors, of the type used for connecting electrical conductor cords to electrically heated appliances, such as toasters, flat irons, and the like.

Connectors of this general type usually comprise a hollow, elongated body of rigid, heat resistant insulating material having two, socket-type contacts supported in side by side relationship within two, open ended recesses formed in the connector body. The connector body usually comprises two, cooperating half-sections. The individual conductors of the conductor cord with which the connector is used are attached to the socket-type contacts within the insulating body by screw fastenings or other means.

During use of the conductor cords and connectors of this type, it is a very common practice for the user to effect the disengagement of the connector from the appliance with which it is used by jerking or pulling the conductor cord. This practice is dangerous, especially when regularly followed, because it almost always results in injury to the cord or to the internal electrical connections and sometimes even to the user. However, the appliance is frequently hot, and it is difficult to convince users not to jerk or pull the cord. As a result, it has been found highly desirable to provide connectors of this style with a strain relief means which shall be effective to transmit tensile stresses applied to the cord directly to the connector body, thereby relieving the electrical connections from strain.

Various arrangements are in use and others have been proposed, but none is completely satisfactory. The principal object of the invention, therefore, is to provide an improved strain relief, for use in conjunction with connectors of the class described, which shall be more efficient and more reliable in operation than the previously known devices, and which, at the same time, shall be simpler and easier to assemble and install in the connectors with which it is used. The means whereby this object is attained, and other objects and advantages of the invention, will be made more apparent in the accompanying drawings and the following description of one illustrative embodiment of the invention.

In the drawings,

Fig. 1 is a plan view showing the strain relief of the invention as installed in a connector of the class described. One of the half sections of the connector body has been cut away to better illustrate the features of the device;

Fig. 2 is a sectional view on the general line 2—2 of Fig. 1;

Figs. 3, 4, and 5 are fragmentary views illustrating three successive steps in preparing the ends of a conductor cord for use with the strain relief of the present invention; and

2

Fig. 6 is a perspective view showing the next succeeding step in the manufacture of the strain relief of the invention.

The body 9 of the connector illustrated in the drawings comprises two, generally rectangularly shaped, cooperating, half sections 11 of a heat resisting insulating material, which are adapted to be securely held together in face to face relation, when the connector is assembled, by a pair of screw fastenings 13, or equivalent means. The opposed faces of the two cooperating half sections 11 are hollowed out so as to define in the assembled connector two, generally parallel, elongated, recesses 15 for receiving two, socket-type, spring contacts 17, which are adapted to cooperate with contact pins or the like, forming a part of the appliance with which the connector is used. The contacts 17 are of conventional type, and the recesses 15 are so formed that the contacts 17 are securely held against any substantially longitudinal movement relative to the plug body when the connector is assembled. The recesses 15 are, of course, open at the outer end to admit the cooperating contact pins or the like.

The conductor cord 19 used in conjunction with the connector illustrated in the drawings is of the usual duplex or two conductor type, and is provided with a braided or rubber jacketed outer covering. Each of the conductors making up the conductor cord 19 includes a metallic cable 21 which is surrounded by a suitable insulating sleeve 23, which is desirably of asbestos or of some other heat-resisting insulating material. The conductor cord 19 is admitted to the interior of the connector body 9 through a generally cylindrical, cord receiving passageway 25 which extends thereto. The inner end of the cord receiving passageway 25 connects with the two, parallel, contact receiving recesses 15 through branch passageways 27, which extend substantially at right angles to the cord receiving passageways 15 and the central axis of the connector body 9.

To minimize bending and kinking of the connector cord adjacent the connector body 9, the connector desirably includes an axially flexible protector spring 29, the lower coils 31 of which are of increased diameter and are adapted to engage an annular recess 33 formed as an enlargement of the cord receiving passageway 25, so as to mechanically connect the spring 29 to the connector body 9. A ferrule 35 may be provided at the outer end of the protector spring for engaging the cord.

In the embodying of the strain relief of the invention into a connector of this type, the braided covering is first removed from the conductor cord 19, so as to expose the two insulated conductors constituting such cord, for a distance about equal to the length of the body portion 9 of the connector, see Fig. 3. The braid end is

then wrapped with thread or the like, as illustrated at 37, to prevent unravelling, and the insulating covering 23 on the two cord conductors is also wrapped to stiffen the insulation and to prevent it from becoming displaced, as illustrated in Fig. 4. A length of the conductor cables suitable for engagement with the connector contacts 17 is bared following the braid removal operation, and preferably preceding the wrapping operation.

Following the wrapping operation, which brings the prepared cord structure into the condition illustrated in Fig. 4, a flat, elongated strip or bar 39, of rectangular cross section and made of relatively strong and rigid insulating material, such as a hard fiber or a molded resin product, is placed between the two wrapped ends of the insulated conductors making up the conductor cord, and those ends are wound around this strip in opposite directions, as indicated by the dotted arrows in Fig. 5, to produce the structure illustrated in Fig. 6. The insulating strip 39 should have a length which is substantially greater than the cord receiving opening 25, and it should have a thickness which is such that the ends of the insulated conductors which are wound around the strip 39, and the strip itself, will be tightly compressed when the two half sections 11 of the connector body are assembled. For the usual type structure wherein the branch passageways 27 have a thickness about twice the diameter of the individual insulated cord conductors, this means that the strip 39 should have a thickness which is about equal to the diameter of the insulated cord conductors. The strip or bar 39, as previously stated, should be of relatively flat construction, and desirably should have a width which is at least about one and a half times its thickness.

During final assembly of the strain relief means, care should be exercised to make sure that the flat sides of the bar 39 will extend substantially parallel to the engaging faces of the co-operating half sections 11 of the connector body. The socket-type contacts 17 may be attached to the cord conductors either before or after the strain relief bar 39 has been put into place.

When the connector has been completely assembled, the various component parts thereof will be in the position shown in Figs. 1 and 2. Any tensional strain applied to the cord 19 will be transmitted to the body 9 of the connector through the strain relief bar 39 and the conductor wrapping applied to that bar. Stressing and possible injury to the electrical connections within the connector is thereby avoided. Because the two ends of the cord conductors which engage the strain relief bar 39 are wrapped around that bar in opposite directions, any tendency of the bar 39 to rotate substantially when stress is applied to the conductor cord is obviated by the oppositely disposed forces set up. The shape of the bar, which produces sharp corners which bite into the cord conductors, and particularly its greater width than thickness, is important in obtaining the objects of the invention.

The strain relief construction of the invention, while very simple in design, inexpensive to manufacture, and easy to assemble, has proven highly efficient. Further, in contrast with many of the known strain resisting arrangements, the construction of the invention does not lose its strain resisting ability after the connector wherein it has been installed has been in use for some time. The oppositely acting forces produced during the strain resisting operation make the ef-

fectiveness of the device independent of the strength of the cord insulation or of any supplementary wrapping, or other means, as is the case in some of the prior art structures, and thus provide a strain relief which is operable and effective so long as the cord conductors themselves are intact. The features of the invention, which are believed to be new, are expressly set forth in the appended claims.

10 I claim the following as my invention:

1. In an electrical connector of the class described, a pair of flat, cooperating, half sections of insulating material assemblable in face to face contact to provide a connector body, said half sections being provided with opposed recesses which provide, when said half sections are assembled, a pair of spaced-apart contact receiving recesses, a centrally disposed, conductor cord receiving passageway, and transversely extending, branch passageways which connect said contact receiving recesses and said cord receiving passageway, contact members occupying said contact receiving recesses, a conductor cord, having a pair of insulated conductors connected respectively to said contact members, occupying said cord receiving passageway, and an elongated, strain relief bar, which is generally rectangular in cross section and which has a width which is substantially greater than its thickness extending across said cord receiving passageway and into each of said transversely extending branch passageways, said bar being disposed flatwise relative to the plane of the engaging faces of the half sections of said connector body, a portion of one of the insulated conductors comprising said conductor cord also occupying each of said branch passageways, the conductor portions occupying said branch passageways being wrapped around said strain relief bar in opposite directions, and the relative proportions of said branch passageways, said bar, and said conductors being such that said conductors and said strain relief bar are tightly compressed and held in position by the co-operating half sections of the connector body when said connector is assembled.

2. In an electrical connector of the class described, a pair of flat, cooperating, half sections of insulating material assemblable in face to face contact to provide a connector body, said half sections being provided with opposed recesses which provide, when said half sections are assembled, a pair of spaced-apart, contact receiving recesses, a centrally disposed, conductor cord receiving passageway, and transversely extending, branch passageways which connect said contact receiving recesses and said cord receiving passageway, contact members occupying said contact receiving recesses, a conductor cord, having a pair of insulated conductors connected respectively to said contact members, occupying said cord receiving passageway, and an elongated, strain relief bar of insulating material which extends across said cord receiving passageway and into each of said branch passageways, said strain relief bar being rectangular in cross section, with sharp corners, having a width which is at least about one and one-half times its thickness, and being disposed flatwise relative to the plane of the engaging faces of the half sections of said connector body, the end portion of each one of the insulated conductors comprising said conductor cord also occupying one of said branch passageways, said end portions being wrapped around said strain relief bar in opposite direc-

tions, and the relative proportions of said branch passageways, said bar and said insulated conductors being such that said end portions and said strain relief bar are tightly engaged by the cooperating half sections of the connector body when said connector is assembled.

3. In an electrical connector of the class described, a pair of flat, co-operating, half sections of insulating material assemblable in face to face contact to provide a connector body, said half sections being provided with opposed recesses which provide, when said half sections are assembled, a pair of spaced-apart contact receiving recesses, a centrally disposed, conductor cord receiving passageway, and a transversely extending passageway which connects said contact receiving recesses and said cord receiving passageway, contact members occupying said contact receiving recesses, a conductor cord having a pair of insulated conductors, each of which is connected to one of said contact members, said conductors occupying said cord receiving passageway, and an elongated, strain relief bar which is generally rectangular in cross-section and which has sharp edges extending across said cord receiv- 25

ing passageway, a portion of each of the insulated conductors comprising said conductor cord being wrapped around said strain relief bar, and the relative proportions of said transversely extending passageway, said bar, and said conductors being such that said conductors and said strain relief bar are tightly compressed and held clamped in position by the co-operating half sections of the connector body when said connector is assembled.
